UNITED STATES PATENT OFFICE.

EDWARD T. SCHOONMAKER, OF NEW YORK, N. Y.

DESIGN FOR AN ANDIRON.

SPECIFICATION forming part of Design No. 21,726, dated July 19, 1892.

Application filed January 27, 1892. Serial No. 419,487. Term of patent 3½ years.

To all whom it may concern:

Be it known that I, EDWARD T. SCHOONMAKER, a citizen of the United States, residing in the city of New York, county of New York and State of New York, have invented a new and original Design for Andirons, of which the following is a specification.

The essential features of my design consist of a column formed of a tapering shaft mounted by a bell-shaped capital and springing from an accumulation of leaves and flowers, a back pin similar in design to the column, two ornamented drums supporting, respectively, the column and the back pin, a curved colonnade formed of a rail and posts and intermediate between the drums, and a curved base supporting the drums and intermediate colonnade.

In the drawings, Figure 1 is a general view of the design; Fig. 2, a plan view in section.

Like letters indicate similar parts in all the drawings.

Fig. 1 shows a tapering shaft Y, surmounted by a bell-shaped capital and starting out of an accumulation of conventional leaves and honeysuckle-flowers tied in the center at X,

the whole forming the completed column Z. This column rests on a drum-shaped block B, which is ornamented by four rosettes and hanging festoons S, applied to its surface at equal distances. This drum B rests upon the lower base D, which retreats upon a curve toward the fireplace, as shown in Fig. 2. The farther end of the base D supports a drum C, upon which rests the back pin O, smaller than but similar in design to the column Z. Between the drums B and C, which support their respective columns Z and O, is a colonnade formed by the rail N and posts P, resting on and following the curve of the base D, as shown in Fig. 1. The posts P are also similar in design to the column Z. The andiron so completed rests upon the feet, as shown, to raise it above the level of the hearth.

What I claim, and desire to secure by Letters Patent, is—

The design for andirons herein shown and specified.

EDWARD T. SCHOONMAKER.
